Specification of Letters Patent.

Patented July 28, 1914.

Application filed August 8, 1912. Serial No. 714,010.

To all whom it may concern:

Be it known that I, ROBERT MIEHLE, a citizen of the United States, and a resident of Chicago, in the county of Cook and State of Illinois, have invented certain new and useful Improvements in Printing-Presses; and I do hereby declare that the following is a full, clear, and exact description thereof, reference being had to the accompanying drawings, and to the letters of reference marked thereon, which form a part of this specification.

This invention relates to that class of flat-bed printing presses having a rotative impression cylinder, a reciprocating type-bed, an inking table connected and moving with the type-bed, inking rollers mounted over the path of the type-bed, an inking table, and ink feeding means, including a fountain and feeding rollers, for supplying ink to the ink table. Such printing presses, as more usually heretofore constructed, have been provided with ink feeding apparatus, including inking rollers for the inking table, 20 located at the delivery end of the machine, sheet delivery mechanism and a piling table or other sheet receiving surface supported on the machine frame at the delivery end of the same and over the ink feeding apparatus. This relative location of the piling table and ink feeding apparatus has been found objectionable for the reason that the ink feeding devices, so located beneath the piling table, is not readily accessible, while 25 the piling table, being located above the ink feeding devices is capable of only a small vertical movement and cannot be lowered to a point near the floor while receiving the printed sheets. In some instances, a piling 30 table so located, has been arranged in such manner that it can be lifted to give access to the inking rollers beneath it, as shown in my prior Patent No. 610,491. In my prior Patent No. 909,199, granted January 12th, 40 1909, I have shown a construction, designed to avoid these objections, wherein the inking apparatus is arranged in the usual position at the delivery end of the press, the piling table or sheet receiving surface is arranged at a considerable distance horizontally from or beyond the delivery end of the press, so as to provide a horizontal passageway and floor space for workmen between the ink fountain and the piling table, and 50 mechanism provided extending across the passageway at an overhead elevation for de-

livering sheets from the press proper to the piling table. This construction affords the advantage of giving convenient access to the ink feeding devices for adjusting the same, 60 and of enabling the piling table to be lowered to the floor, but it has the disadvantage of requiring that the sheet delivery devices be made of undue length in order to carry the sheets over the said passageway, and of 65 occupying a large amount of floor space in the press room.

My present invention is designed to avoid the objections stated to both of the forms of presses and sheet conveying and receiving 70 devices referred to, and also to provide a form of ink-feeding device adapted to supply the ink to the ink-table throughout the entire length of the same.

An apparatus embodying my said invention embraces, in general, features as follows: The ink feeding device is mounted on the frame of the machine and extends over the table at a point between the inner and outer ends of the path of movement of the 75 ink-table. The ink fountain of such ink-feeding device is located at a considerable distance above the ink-table, and the inking rollers associated therewith are arranged to carry the ink downward therefrom to the 80 ink table, so that the said fountain and inking rollers occupy only a relatively short space in a direction lengthwise of the press. The sheet receiving means is located outside of or beyond, but closely adjacent to, the 85 delivery end of the press, and the sheet delivery mechanism extends from the upper part of the compression cylinder to the sheet receiving means, at a considerable elevation above the ink feeding device. Such sheet 90 receiving means may include a vertically moving piling table, or may consist of another printing press to which the sheets are delivered. By reason of the relative location and arrangement of the sheet delivery 95 and receiving devices, and the ink-feeding means, the latter is made to act on the entire length of the ink table, so that the latter may be made shorter than heretofore, and less room will be occupied by the ink table 100 when at the end of its outward stroke, while the apparatus as a whole will occupy less floor space than heretofore and the ink fountain is made conveniently accessible, for the purpose of accurately adjusting the feed of 105 ink to the ink table.

The invention consists in the matters here-

inafter described and more particularly pointed out in the appended claims.

As shown in the accompanying drawings—Figure 1 is a side view of the delivery end of the printing press of the type known as a two-revolution flat bed press, together with a vertically movable piling table and sheet delivery means; Fig 2 is a fragmentary plan view of the press shown in Fig. 1; Fig. 3 is a view in end elevation, with parts broken away, of the press shown in Figs. 1 and 2; Fig. 4 is a fragmentary side view of the press, showing a modified arrangement of the ink feeding devices; Fig. 5 is a view in side elevation of two printing presses of the kind shown in Fig. 1, arranged end to end, so that the delivery end of one press is adjacent to the receiving end of the other, in connection with sheet delivery devices adapted to deliver sheets from one press to the other.

The printing press illustrated is one of a well-known type of flat-bed presses, comprising a rotative impression cylinder 5, a horizontal, reciprocating type-bed 6 and an ink table 7. Said ink-table is rigidly secured upon the bed at one end of the same and the bed is given endwise reciprocatory movement through the medium of a well-known form of actuating device, embracing a frame 8 attached to and depending from the bottom of the bed, upwardly and downwardly facing rack bars 8^a, 8^b on said frame, a gear-wheel 9 mounted on a shaft 10, and adapted to mesh with one or the other of said rack bars, and a roller 9^a carried by a crank arm 9^b on said rock shaft 10; said roller 9^a acting in vertical slots at the ends of said frame 8. A vertically movable sheet-receiving or piling table 11 is located adjacent to the delivery end of the press. Said piling table is shown as supported by suspension cables 11^a, 11^b. At the delivery end of the machine each of the side frame plates 12 thereof has attached to it an upright frame piece or standard 13, provided at its upper end with a longitudinally extending frame arm 14. The two frame arms 14, at opposite sides of the machine frame, constitute the side frame members of the sheet carrying and sheet delivery apparatus which is employed for the delivery of sheets from the impression cylinder to the piling table. The sheet conveying means, by which the sheets are carried from the impression cylinder over the type-bed and ink-table to the sheet delivery device, includes upper and lower tape rollers 15, 16 mounted on the main frame of the machine adjacent to the impression roller 5, like upper and lower tape rollers 17 and 18, mounted between the frame arms 14, 14 adjacent to the top of the standards 13, 13 and tapes or bands 20, 21, which are trained around the several tape rollers, in a familiar manner. The tapes 20,

21, or other sheet carrying means, extend in a substantially horizontal direction from the top of the impression cylinder, so that they are carried over the machine at a high elevation above the ink fountain and ink feeding devices. The sheets which are carried from the impression roller by the action of the tapes 20 and 21 are delivered to the piling table through the medium of a suitable sheet delivery device, such as that shown in my prior Patent No. 909,199, issued January 12, 1909. A portion only of such delivery device is shown in the accompanying drawings, and as the details of the delivery device have no relation to the present invention, it is not necessary to herein describe them.

The machine is provided with two pairs of form inking rollers 23, 23 extending over the type-bed adjacent to the impression cylinder 5, as heretofore commonly used in similar presses. Said form rollers are given rotative movement by frictional contact with the rider rollers 26, 26, said rollers being positively rotated through the medium of gearing, embracing a horizontal rack-bar 24, carried by the reciprocating type-bed, and a gear wheel 25, which has intermeshing engagement with said rack-bar, and a series of gear pinions by which said rider rollers are driven from said gear wheel.

The devices for supplying ink to the ink table are located above the path of said table and extend across or over the same between the outer and the inner ends of the path of movement of the ink table. In other words, the ink supplying or feeding devices are located at such distance from the delivery end of the machine that they act upon, or operate to supply ink to the inner portion of the ink-table, when said table is at the limit of its advance or outward movement. In the preferred construction illustrated in the drawings, said ink-feeding devices are located at such distances from the delivery end of the machine that the ink will be supplied to and distributed upon the table throughout the entire length of the same, instead of being supplied to the rear end or portion only of said ink-table and distributed thereupon by distributing rolls, as common in like printing presses as heretofore usually constructed.

The ink feeding devices shown in the drawings embrace an ink receptacle or fountain 30 which is located at a considerable distance above the level of the top of the ink table and is supported at its ends upon upwardly extending arms or brackets 31 attached to the side frame plates 12 of the machine. Said ink fountain is shown as provided with the usual adjusting screws 30^a for accurately controlling the amount of ink supplied to different parts of the width of the ink-table. The ink-feeding devices also include two ink-applying rollers 32, 32, the bottom surfaces of which are adapted for 130

contact with the top of the ink table. A transfer roller 33 is located centrally above and in contact with both of the rollers 32, 32. Another transfer or riding roller 34 is mounted above and in contact with the roller 33. Said roller 34 is located nearly at the level of and a short distance laterally from a roller 35, that is located within the ink fountain or receptacle. An oscillating ductor roller 36, operating in a familiar manner, is adapted to transfer the ink from the surface of the fountain roller 35 to the transfer roller 34. A freely rotating distributing roller 37 is located above and rests by gravity upon roller 34. Said rollers 34 and 37 are mounted at their ends in brackets 38 which are attached to and rise from the side plates 12 of the machine.

The roller 33 is shown as being positively actuated or driven in such manner that it turns or rotates alternately in opposite directions, according to the direction of movement of the type-bed and ink-table, and its rotative movement is transmitted to the inking rollers 32, 32, which come directly in contact with the ink table. For giving rotative movement to said roller 33 devices are provided as follows: Attached to one end of said roller 33, inside of the bearing bracket 38, is a gear pinion 39. Said gear pinion meshes with an idler pinion 40 mounted on the inner face of the said bracket. Said idler pinion 40 intermeshes with a gear pinion 41 also mounted on the inner face of the said bracket. Rigidly connected with the gear pinion 41, at one side of the same (Fig. 3), is a sprocket wheel 43. The gear pinion 41 is driven through the medium of a sprocket chain 42 which passes around the sprocket wheel 43 and around another sprocket wheel 44 located adjacent to the form-inking rollers. Said sprocket wheel 44 is attached to and turns with one of the series of gear-pinions by which the said form-rollers are operated from the gear wheel 25, hereinbefore referred to.

The oscillating or ductor roller 36 is shown as mounted to the upper ends of oscillating arms 50, 50, which are attached to a transverse rock shaft 51. To one end of said rock shaft is attached an operating arm or lever 52. Actuating devices for giving oscillatory movement to the said lever arm 52, as illustrated, consist of a rotative cam 53, a rocking lever 54, one arm of which bears upon and is operated by said cam, a connecting rod 55, connecting the opposite arm of said rocking lever 54 with the actuating arm 52, and a spring 56, which acts on the connecting rod 55 in a direction to hold the lever 54 in engagement with said cam 53.

An important feature of the ink-supplying device, above described, is that the ink fountain or receptacle is located at a con-

siderable distance vertically above the ink table, and the ink-carrying or transferring rollers, by which the ink is transferred from said ink fountain to the ink-table, are so disposed as to carry or conduct the ink downward, in a substantially vertical path, from the ink fountain to said ink-applying rollers. In other words, the arrangement of the several rollers referred to is such that the roller 34 is located near the level of, and at the proper distance laterally from, the roller 35 in the ink fountain for the proper transfer of the ink to said roller 34, through the action of the oscillating ductor roller 36, while the intermediate transfer roller 33 and the ink applying rollers 32, 32 are located vertically below the rollers 34, 35 and 36. As a result of the arrangement of the ink fountain and ink-transferring rollers described, the ink feeding devices as a whole occupy only a short space in a horizontal direction, lengthwise of the machine, and a much smaller space in the direction stated than in the case of ink-feeding devices heretofore usually employed, wherein the ink is carried or transferred horizontally from an ink fountain located at the delivery end of the machine, by a ductor roller acting on the rear end of the ink table. By reason of the short space occupied by the inking rollers longitudinally of the ink table and the arrangement of parts by which said rollers act on said ink table throughout the entire or a large part of its length, and because of the fact that the transfer and inking rollers are positively driven, the ink is uniformly distributed on the ink-applying rollers and uniformly delivered therefrom to the ink table, thereby insuring proper distribution of the ink on the ink table without the use of a ductor roller and distributing rollers acting directly on the ink table and avoiding the necessity of using such a long ink table as in such case required. Moreover, by the shortening of the ink table, a considerable amount of space is saved at the delivery end of the machine, so that less floor space is required for the press, while convenient access may be had to the ink fountain. It is, of course, understood that accessibility to the fountain is necessary in order that the supply of ink to the different parts of the width of the ink table may be controlled through the operation of the adjusting screws 30^a or other controlling devices on the ink fountain. The open spaces at the sides of the ink-feeding devices, afforded by reason of the location of the sheet-carrying means at a high elevation above the ink table, and the arrangement of the ink-feeding device, as described, enable the operator to readily obtain access from the sides of the machine to all parts of the ink-feeding device, when the piling table is located closely adjacent to

the delivery end of the machine, and access may likewise be had to the ink fountain from the delivery end of the press when a space is provided for the passage of the operator between the said piling table and such delivery end of the machine. The elevation of the ink fountain to a considerable distance above the ink table and the arrangement of the ink-carrying or transferring 10 rollers in a group extending in a vertical, instead of a horizontal, direction, contributes to the saving of floor space, because enabling a shorter ink table to be used, as above stated. The elevated position of the ink fountain also facilitates access to the feed-adjusting screws 30^a, which are located at the lower part of the inclined outer wall of the said fountain.

In connection with the ink feeding devices arranged as described, a fixed horizontal board or table 57 is provided, which is located above the path of the ink table and which extends from the ink fountain or reservoir 30 to the rear or delivery end 25 of the machine. Said table serves to prevent the arms or hands of the operator coming in contact with the ink table in the act of adjusting the feed-controlling devices of the ink fountain, and provides a rest for the 30 arms, or a part of the body of the operator, so far as is necessary, while so adjusting said feed-controlling devices. Said fixed table is preferably extended at the delivery end of the machine to a point above the 35 outer extremity of the path of the ink table, so that it extends over said ink table when the latter is in its rearmost position, as clearly shown in Fig. 1. Said table also provides a support for one of the sheets, 40 printed from the form in the press, so as to enable the operator to easily effect adjustment of the ink fountain to correct irregularities in the supply of ink, as shown by the impression previously made on such 45 sheet.

In Fig. 4 I have shown a construction in the ink-feeding device, which is like that shown in Figs. 1 to 3, and hereinbefore described, with the exception that the location of the ink fountain and the ink-transferring rollers associated therewith, is reversed, so that the ink fountain is nearest the impression roller or the receiving end of the machine and the said rollers are 55 nearest the delivery end of the same. Except for the reversal in location referred to, these parts are like those hereinbefore described and are indicated by corresponding numerals in the drawings. In this instance, 60 a board or table 58, corresponding with the table 57, is located over the type-bed and extends longitudinally of the machine from the ink fountain toward the impression cylinder 5. When the parts are constructed as 65 shown in Fig. 4, the operator is enabled to

reach the feed adjusting means upon the ink fountain when standing at either side of the machine, opposite the space between the ink-feeding devices and the form rollers 23, 23. In the arrangement of the ink-feeding device shown in Fig. 4, as well as in that shown in Figs. 1 to 3, the elevation of the ink fountain above the ink table and the arrangement of the ink-transferring rollers in a vertically extending group, as well as 70 the elevation of the carrying tapes 20 and 21, or the sheet-conveying means, above the said ink-table, gives ample room or space through which the operator may easily reach all parts of the ink-feeding devices 80 from the sides of the machine.

In Fig. 5 I have shown the parts of two printing presses of the same general character as that illustrated in Figs. 1 and 2, the same being placed end to end, as closely 85 together as possible, and so arranged that the sheets delivered from one press are received by the other press in position to be fed to the impression cylinder of the same. In this instance, the receiving press is provided at its receiving end with the usual frame standards 60, 60 carrying frame bars 61 on which is mounted a feed table 62. Attached to each frame bar 61 is a bracket 63 carrying upper and lower rollers 64 and 65. Sheet-carrying tapes 66 and 67 are trained over said rollers 64 and 65, the same corresponding with the tapes 20 and 21, shown in Fig. 1. A third roller 68 is mounted in the brackets 63 and another roller 69 is 90 mounted on the feed table 62 near the impression roller 5. Tapes 70 pass around the rollers 68 and 69 and are arranged to convey the printed sheets delivered from the tapes 66 and 67 over the guide fingers 71 95 on the rear end of the feed table, to the impression cylinder. In this instance, the left-hand press, from which the sheets are delivered, is not provided with sheet delivery devices, but the printed sheets are 100 transferred by the tapes 66 and 67 from the impression cylinder of the left hand press directly to the sheet-feeding devices of the right-hand press, shown in said Fig. 5.

In the press shown at the left hand side 115 of Fig. 5, the sheet conveying device, consisting, in the instance shown, of the tapes 66 and 67, is located a considerable distance above the ink-feeding device, so as to afford ample space beneath the said sheet delivery 120 devices to permit the operator standing at the sides of the press to have free access to the ink-fountain, as required for controlling the feed of ink from said ink fountain to the ink-table.

A further advantage gained by the construction described in the ink table and means for supplying ink thereto is that the same enables the ink table to be made shorter in length than heretofore, and the space re- 125

quired for the outward stroke of such ink table correspondingly decreased, so that the apparatus as a whole occupies less floor space. In prior constructions, in which the 5 ink fountain is located exterior to the outer end of the path of the ink table, the latter is made of such length as to provide for the action thereon of the ductor roller at its outer end; but in the present construction, 10 wherein the ink fountain and transfer and ink-applying rollers are located inwardly from the outer end of the path of the ink table and the ink is distributed by the rotation of such rollers, the ink table may be 15 made shorter to an extent equal to the part of the ink table acted on by the ductor roller in prior devices.

Referring to Fig. 5, it will be observed that, while the two presses therein shown 20 are located closely together, yet, by reason of the shortness of the ink table 7, when the latter is advanced a space is still left between the press frames in which the operator can stand when adjusting the feed of the 25 ink fountain or when inspecting a proof impression resting on the table 57, for the purpose of accurately adjusting the feed of ink to different parts of the width of the ink table, according to the requirements indicated by the proof impression. Likewise, 30 in the construction shown in Fig. 1, it will be seen that the shortened length of the ink table will enable the piling table 11 to be placed nearer the end of the machine frame 35 than when the ink fountain is there located and a ductor roller is employed to convey the ink to the end portion of the ink table. Moreover, if, in the construction shown in Fig. 1, a slightly greater space is left between the piling table 11 and the adjacent 40 end of the press frame, the operator may stand between the piling table and the end of the ink table, for the inspection of a proof sheet laid on the table 57 and adjustment of the ink fountain, without liability 45 of being struck by the ink table in the outward movement of the latter. In the construction shown, the fixed table 57 is extended at its outer edge to a point in substantially vertical alinement with the outer edge 50 of the ink table when the same is at the extreme limit of its outward movement, so that the outer edge of said table 57 constitutes a guard to prevent the ink table striking the operator when standing at the outer end 55 of the ink table in a position convenient for adjusting the ink fountain, or for inspecting a proof sheet resting on the table 57.

The location of the ink fountain above the 60 inner end of the path of the ink table and the employment of ink-transferring and applying rollers arranged in a vertically extending group adapted to carry the ink downwardly from the ink fountain to the 65 ink table, when the ink transferring or ap-

plying rollers are positively and constantly driven, as in the construction shown, has the advantage that the delivery of ink to and its distribution upon the ink-applying rollers 32, 32 is taking place when the ink 70 table is out of contact with the said rollers 32, 32, and is passing beneath the form rollers 23, 23, so that in the outward stroke of the ink table the latter receives, from the rollers 32, 32, ink which has been uniformly 75 distributed thereon by the action of the transferring rollers and the rotation of said rollers 32, 32, independently of the movement of the ink table. In the construction described and illustrated, therefore, notwithstanding that the ink table is made shorter than is possible in cases in which the ink is applied to the outer end thereof by a ductor roller thereon acting, the ink is thoroughly and uniformly applied to and distributed upon the ink table. An important 80 feature of my invention, however, resides in the feature of construction by which the elevated ink-fountain and its associated vertically extending group of ink-transferring 85 rollers are located adjacent to the inner end of the path of the ink-table, and in such relation to the latter that the ink-applying rollers 32, 32 will act on the ink-table throughout substantially the entire length of 90 the same. The last-mentioned feature of construction has the advantage of providing for the supply of ink along the entire length of the ink table and its even distribution 95 therein by the action of the rollers that operate to convey the ink thereto.

It is to be understood that a printing press embracing the features constituting my invention may be variously modified with respect to its details, and I do not desire to be limited to the specific features shown in the accompanying drawings, except so far as pointed out in the appended claims.

I claim as my invention:

1. In a printing press, the combination of a machine frame, an impression cylinder, a horizontal endwise reciprocating type bed, an ink table movable with the type bed, sheet receiving means located at the delivery end of the machine frame beyond the path of the ink table, sheet conveying devices extending from the impression cylinder at an elevation above the type bed and beyond the delivery end of the machine frame, and adapted to deliver the sheets to the receiving means, form inking rollers located adjacent to the impression cylinder in position for the passage of the ink table beneath the same, an ink fountain mounted upon the machine frame at a distance above the level of the ink table, a plurality of ink transferring and applying rollers, arranged in a vertically extending group and adapted to transfer the ink from the ink fountain down- 130

wardly to the ink table, said ink fountain and transferring and applying rollers being located between the outer end of the path of movement of the ink table and the outer end 5 of the frame and actuating means giving rotative movement to said ink transferring and applying rollers.

2. In a printing press, the combination of a machine frame, an impression cylinder, a 10 horizontal endwise reciprocating type bed, a horizontal ink table moving with the type bed, sheet receiving means located at the delivery end of the machine and embracing a piling table movable in a vertical path adjacent to the outer end of the path of the ink table, sheet conveying devices extending from the impression cylinder at an elevation above the type bed and ink table and adapted to deliver the sheets to the piling table, form 15 inking rollers located adjacent to the impression roller in position for the passage of the ink table beneath the same, an ink fountain supported on the frame of the machine at a distance above the level of the ink 20 table, a plurality of ink transferring and applying rollers arranged in a vertically extending group, and adapted to convey the ink from said ink fountain downwardly to said ink table, said ink fountain and ink 25 transferring and applying rollers being located between the outer and inner ends of the path of movement of the ink table, and actuating means imparting rotative movement to said transferring and applying 30 rollers.

3. In a printing press, the combination of a machine frame, an impression cylinder, a horizontal reciprocating type bed, an ink 40 table moving with the type bed, an ink fountain mounted upon the machine frame above the level of the ink table and provided with means for controlling the flow of ink therefrom, a plurality of vertically arranged ink transferring and applying rollers 45 adapted to transfer the ink from said ink fountain downwardly to the ink table, said ink fountain and transferring and applying rollers being located inwardly from the outer end of the path of movement of 50 the ink table, and a fixed table mounted upon the machine frame above the ink table and below the level of the ink fountain, with one of its edges adjacent to the ink delivery 55 controlling means of said fountain.

4. In a printing press, the combination of a machine frame, an impression cylinder, a horizontal reciprocating type bed, an ink table moving with the type bed, an ink fountain mounted upon the machine frame 60 above the level of the ink table and provided with means for controlling the flow of ink therefrom, a plurality of vertically arranged ink transferring and applying

rollers adapted to transfer the ink from said ink fountain downwardly to the ink 65 table, said ink fountain and transferring and applying rollers being located inwardly from the outer end of the path of movement of the ink table, and a fixed member mounted upon the machine frame and extending 70 across the same above the ink table and adjacent to the outer end of the said ink table when the latter is at the outward limit of its stroke; said fixed member forming a guard 75 for the operator.

5. In a printing press, the combination of a machine frame, an impression cylinder, a horizontal reciprocating type bed, an ink table moving with the type bed, a vertically movable sheet receiving means located adjacent to the delivery end of the machine and beyond the path of the ink table, sheet conveying devices extending from said impression cylinder at an elevation above the type bed to the sheet receiving means, an ink 80 fountain mounted above said ink table and located inwardly from the delivery end of the machine adjacent to the inner end of the path of movement of the ink table, a plurality of ink transferring rollers arranged 85 in a vertically extending group and adapted to transfer the ink from the ink fountain downwardly to the ink table, and a fixed table mounted above said type bed and below the ink fountain and extending from 90 said ink fountain toward the delivery end of the machine.

6. In a printing press, the combination of a machine frame, an impression cylinder, a horizontal reciprocating type bed, an ink 100 table moving with the type bed, a plurality of form-inking rollers located adjacent to the impression cylinder and in position for the passage of the ink table beneath the same, an ink fountain mounted upon the machine frame above the ink table, and located inwardly from the delivery end of the machine and adjacent to the inner end of the path of movement of the ink table, a plurality of ink transferring rollers arranged 105 in a vertically extending group and adapted to transfer the ink from the ink fountain downwardly to the ink table, throughout substantially the entire length 110 of the said ink table, and a fixed table 115 mounted immediately above the said ink table and extending from said ink fountain toward the delivery end of the machine.

In testimony, that I claim the foregoing as my invention I affix my signature in the presence of two witnesses, this 5th day of

August A. D. 1912.
